POT-TYPE OIL BURNER WITH A CIRCUMFERENTIAL VAPORIZING CHAMBER

Edward H. Stempel and Marcus Nelson, Albert Lea, Minn., assignors to American Gas Machine Company, Albert Lea, Minn., a corporation of Minnesota

Application July 27, 1945, Serial No. 607,382

7 Claims. (Cl. 158—91)

1

This invention relates to oil burners of the pot type.

It is one of the objects of the invention to provide a novel and improved pot-type oil burner of cheap and simple construction which can be burned at pilot flame, intermediate flame and high flame depending upon the amount of oil supplied to the burner.

Another object is to provide in a pot-type oil burner improved means for introducing secondary combustion air to the pot, whereby the operation of the burner at high flame is greatly improved.

The objects and advantages of the invention will more fully appear from the following description, made in connection with the accompanying drawings, wherein an exemplification of the invention is shown and wherein like reference characters refer to the same or similar parts throughout the various views, and, in which:

Figure 1 is a plan view of the oil burner, certain of the parts being broken away and others shown in section to more clearly illustrate the construction thereof;

Figure 2 is a view partly in side elevation and partly in vertical section through the oil burner, part of the drawing shown in section being taken substantially on the line 2—2 of Figure 1;

Figure 3 is a horizontal section taken on the line 3—3 of Figure 2; and

Figure 4 is a detailed view in vertical section taken on the line 4—4 of Figure 3 as indicated by the arrows.

While the pot of the oil burner can be variously constructed, there is in accordance with the illustrated embodiment, an entire pot bottom A formed of one piece of metal, a tubular side wall B formed of a second piece, a cowling C formed of a third piece, a deflector ring D formed of a fourth piece, an air director ring E formed of a fifth piece and a flame confining ring F formed of a sixth piece. The pot bottom A is provided at its side near its upper edge with an offset flange 5 within which the side wall B is received, and the side wall B is provided at its top with an out-turned flange 6 on which the air director ring E rests. The air deflector ring D in turn, rests on the air director ring E and projects well inwardly therefrom, and at its outer edge, the air director ring is equipped with a down-turned flange 7 which encompasses the outer edges of the flange 6 and the air director ring E. The flame confining ring F rests on the air deflector ring D and extends to a point above it. In practice, the parts may be permanently

2

secured together to better hold their positions as by spot welding, riveting or the like.

The pot bottom A at its outer lower portion is curved to form an annular trough 8, the inner wall of which forms a rib or dam 9 spaced above the level of the bottom of the trough 8 and extending through approximately 340 degrees of a circle. Also, the dam 9 forms the upper edge of a concavely curved dish 10 which closes the central part of the pot bottom A and which is at least as deep as the trough 8. At the point where the pot bottom A is not pressed up to form a continuation of the dam 9 the pot bottom is curved downwardly to form a channel 11 leading from the trough 8 to the center of the dish 10 and, as will be clearly seen from Fig. 4 of the drawings, the lower part of this channel 11 is as deep as the trough 8 so that any liquid flowing around the trough 8 to the channel 11 may pour therethrough into the central part of the dish 10.

The cowl C as shown, extends upwardly through roughly, a third of the height of side wall B and is provided with an upturned flange 25 at its upper end which fits with close clearance the interior of the wall B. From said flange 25 the cowl C curves inwardly and downwardly to contact the dish 10 in somewhat inwardly spaced relation to the annular dam 9. The cowl C, the outer part of the pot bottom A, and the lower part of the side wall B thus form an annular chamber 12 which will be called a vaporizing chamber in accordance with its function. Immediately above the channel 11, the cowl C is deeply notched upwardly to form with a portion 30 of the channel 11 a passage 13 affording communication between the chamber 12 and the central part of the pot above the dish 10. At circumferentially spaced points from each other and from the channel 13 the cowl C is notched 35 upwardly from its lower edge to form one or more additional passages 14 in cooperation with the dish 10 and also affording communication between the vaporizing chamber 12 and the central part of the pot above the dish 10. It should be noted that the lower parts of the passages 14 40 are well above the level of the channel 11 for a purpose to presently appear. In actual practice the notches in the cowl plate C and forming portions of the passages 13 and 14 are set circumferentially at 120° from each other although this is not absolutely necessary.

Affording communication with the vaporizing chamber 12 at a point diametrically opposite the passage 13 is an oil delivering conduit 15 for supplying liquid hydrocarbon from a source of sup-

ply to the pot. The flow of oil through the conduit 15 may be controlled in any desired manner to vary the quantity of flow and for ease in illustration there is merely shown in the illustrated embodiment a hand-controlled valve 16 for this purpose. In commercial installations other controls will be employed such as are commonly used in conjunction with other oil burners now on the market.

Below the level where the cowling C is attached to the side wall B the side wall is provided with a multiplicity of perforations circumferentially spaced from each other and forming openings 17 leading into the vaporizing chamber 12 and supplying vaporizing air thereto. In order that the air admitted through the openings 17 into the chamber 12 may be better directed downwardly to mix with oil in the trough 8, at the time the openings are formed, the metal is perforated in a downwardly and inwardly angular direction as is well known in the art.

Above the level where the cowl plate C joins the side wall B, and at several different levels, primary combustion air openings 18 are formed in the side wall B, air from these openings running into the central part of the pot above the dish 10.

The deflector ring D near its edge but inwardly from the side wall B is provided with a multiplicity of vertical openings 19, and these openings are for the purpose of supplying secondary combustion air for high flame operation of the burner. It will be noted that the air must pass through these openings 19 in a downward direction. The air director ring E has a flange 20 spaced a short distance below the deflector ring D and immediately below the secondary air inlet openings 19, and this flange 20 acts to direct the air running through the openings 19 inwardly of the burner so this air takes a diagonally downward and inward course. The deflector ring D has a downwardly extending flange 21 at its inner edge which also has some air deflecting action and tends to prevent straight horizontal movement of air from the secondary air openings 19 to the center of the burner.

The flame confining ring F is attached to the deflector ring D preferably just inwardly of the openings 19 and it has a first step 22 which is inwardly directed and which is spaced a short distance above the deflector ring D and has a second step 23 which is spaced above the step 22 and also inwardly directed. The ring F functions to confine the flames when the burner is in high flame operation and prevent flames from spreading outwardly to too great an extent.

In the operation of the burner the burner will normally be lighted as by throwing a small scrap of paper or a match into the pot when sufficient oil is being supplied as by controlling the valve 16 for low flame operation. As the valve 16 is opened oil will be supplied to the conduit 15 into the trough 8 and will flow out after making the circuit of the trough through the channel 11 into the central part of the dish 10. When sufficient oil has been accumulated this oil may be lighted by a match or paper as aforesaid. Some air will be supplied through the openings 17, chamber 12 and passages 13 and 14 to supply this initial ignition, but the major part of the air will be supplied through the primary air supply openings 18. After the burner has operated at low flame for a time with the flame confined well within the lower part of the pot, the lower part of the pot will become highly heated and, of course, the air within the vaporizing chamber 12 will also become

highly heated. Eventually this heat will be sufficient so that the small quantity of oil supplied through the channel for low flame operation will be very largely vaporized within the chamber 12, the oil being completely vaporized before it reaches the central part of the dish 10. By cutting off the supply of fuel to a greater extent as by manipulating the valve 16 to a more closed position the burner will operate so as to vaporize all of the oil before the oil has traveled around the trough 8 from its admission point through the conduit 15 past one or both of the passages 14. In other words, vaporized fuel in small quantities will then issue from one or more of the passages 14 and burn as issued therefrom, thereby forming a pilot flame for ignition when greater quantities of fuel are admitted to the burner to operate it either at low flame, intermediate flame or high flame.

With our improved structure, a substantially infinite number of flames and consequently, heat generating intensities may be obtained progressively from the low, pilot flame to the high flame dependent upon the adjustment of the regulating valve 16 and the control of fuel introduced through conduit 15, per unit of time.

To operate the burner at high flame a greater quantity of fuel is supplied through the fuel conduit 15 as by opening the valve 16 widely and gradually the burner goes successively from pilot flame operation to low flame operation and then to high flame operation. The oil supply at this time is too much to be entirely vaporized within the vaporizing chamber 12 and it passes in two branches completely around the trough 8 to pour through the channel 11 into the central part of the dish 10. There it is supplied with primary air admitted to the interior of the pot through the openings 18. Gradually the flame rises in the burner so that it extends well up into the upper part of the pot and is then supplied with secondary air admitted through the secondary air openings 19. Because of the direction that this secondary air must take by reason of the vertical disposition of the openings 19, the air director ring E and the flange 21, the secondary air works into the flame in a downwardly and inwardly extending direction, thereby mixing with the products of combustion within the pot to a greater extent and more thoroughly than is the case in burners wherein the secondary air is directed upwardly and inwardly. The ring F tends to confine the flame by its two steps 22 and 23 when the burner is in high flame operation.

It will be seen that a highly efficient, simple and economical pot type oil burner has been provided.

It will, of course, be understood that various changes may be made in the form, details, arrangement and proportions of the various parts without departure from the scope of the present invention which generally stated, consists in the matter shown, described, and set forth in the appended claims.

What we claim is:

1. An oil burner comprising, a pot bottom having an annular trough in its outer portion, the inner wall of which trough forms a dam throughout most of the circumference of the pot bottom, said pot bottom being depressed inwardly from said dam to form a dish, and the inner wall of said trough being depressed at one point between portions of said dam to form a flow channel from the lower part of said trough to the lower part of

said dish, an annular side wall upstanding at the outer side of said pot bottom, said annular wall being perforated at various levels to form openings for air admission above said trough and also openings for primary combustion air to the interior of the pot, a cowling joining said side wall and the upper part of said dish above certain of said openings and combining with portions of said pot bottom and said side wall to form a vaporizing chamber, said cowling having openings therein at three circumferentially spaced points, one of which openings is located directly above said channel to form with said channel a first passage from said chamber to the interior of the pot above the dish and the other openings forming second passages above the dam level from said chamber to the interior of the pot above said dish, a valve controlled oil conduit for delivering liquid fuel from a source of supply to said chamber, said oil conduit delivering into said chamber at a point remote from said first passage and between said two second passages, an inwardly directed deflecting ring resting on said side wall at the top of the pot, and means for delivering secondary combustion air at the upper portion of the pot.

2. An oil burner comprising a pot having a closed bottom and an opening in its upper portion and including means forming an outer circumferential vaporizing chamber in the lower portion of said pot, said chamber extending substantially entirely around the bottom of said pot, there being an upstanding dam in the lower portion of said chamber spaced inwardly from the outer portion thereof and forming an oil trough within the chamber, a dish inwardly from said dam, passage means including an oil passageway through said dam affording communication between said chamber and said dish, valve controlled conduit means for delivering liquid fuel from a source of supply to said chamber, said conduit means communicating with the trough in said chamber at an area of said trough that is in non-communication with the oil passageway through said dam for at least substantially half the extent of the trough, means for supplying air to said chamber, means for supplying primary combustion air to said pot and means in the upper part of said pot for supplying secondary combustion air.

3. An oil burner comprising a pot having an opening in its upper portion and including means forming an outer vaporizing chamber in the lower portion of the pot and having an upstanding dam in the lower portion of said chamber spaced inwardly from the outer portion thereof and forming an oil trough in said chamber, a dish inwardly from said dam, first passage means between said chamber and said dish including an oil passageway through said dam, second passage means between said chamber and said dish above the lowest level of said first passage means and spaced along said trough from said first passage means and affording communication from said chamber to said dish at a level well above the lowest level of said first passage, a valve controlled conduit for delivering liquid fuel from a source of supply and communicating with said trough at a point more adjacent to said second passage means than to said first passage means, means for supplying air to said chamber, means for supplying primary combustion air to said pot, and means in the upper part of said pot for supplying secondary combustion air.

4. An oil burner comprising a pot having an opening in its upper portion and including means

forming an outer vaporizing chamber in the lower portion of the pot, there being an upstanding dam in the lower portion of said chamber spaced inwardly from the outer portion thereof and forming an oil trough in said chamber, a dish inwardly from said dam and running to at least the depth of said trough, first passage means between said chamber and said dish including an oil passageway through said dam, the lower part of the passage formed by said first passage means being located at a level at least as low as the lower level of said trough, second passage means spaced along said trough from said first passage means and affording communication from said chamber to said dish at a level well above the lowest level of said first passage, a valve controlled conduit for delivering liquid fuel from a source of supply and communicating with said trough at a point more adjacent to said second passage means than to said first passage means, means for supplying air to said chamber, means for supplying primary combustion air to said pot, and means in the upper part of said pot for supplying secondary combustion air.

5. An oil burner comprising a pot having an opening in its upper portion and including means forming an outer annular vaporizing chamber in the lower portion of the pot, there being an upstanding dam in the lower portion of said chamber spaced inwardly from the outer portion thereof and forming a trough in said chamber, a concave dish joining said dam and inwardly disposed therefrom, said dish running to at least the depth of said trough, first passage means affording communication between said chamber and the interior of said pot above said dish including an oil passage from said trough through said dam, the lower level of the first passage formed by said first passage means being at least as low as the lower level of said trough, second passage means affording communication between said chamber and the interior of said pot above said dish and spaced along said trough from said first passage means, the lower level of the passage formed by said second passage means being well above the lower level of said first passage, a valve controlled oil conduit for delivering liquid fuel from a source of supply to said chamber and communicating with said trough at a point more closely adjacent said second passage means than said first passage means, means for supplying air to said chamber, means for supplying primary combustion air to the interior of said pot, and means for supplying secondary combustion air at the upper portion of said pot.

6. An oil burner comprising a cylindrical pot having an opening in its upper portion and having means forming an outer annular vaporizing chamber in its lower portion and having an upstanding dam in the lower portion of said chamber spaced inwardly from the outer portion thereof and forming a trough in said chamber, a concave dish joining the said dam and inwardly disposed therefrom, said dish running to at least the depth of said trough, first passage means affording communication between said chamber and the interior of said pot above said dish including an oil passage from said trough through said dam, the lower level of the first passage formed by said first passage means being below the level of said dam, a pair of second passage means affording communication between said chamber and the interior of said pot above said dish, the lower level of the second passages formed by the said second passage means being

above the level of said dam, and said second passage means being circumferentially spaced from each other and from said first passage means, a valve controlled oil conduit for delivering liquid fuel from a source of supply and communicating with said chamber between said two second passage means at a point remote from said first passage means, means for supplying air to said chamber, means for supplying primary combustion air to said pot, and means in the upper part 10 of said pot for supplying secondary combustion air.

7. An oil burner comprising a pot having a closed bottom and an opening in its upper portion and including means forming an outer circumferential vaporizing chamber in the lower portion of the pot, said chamber extending substantially entirely around the bottom of the pot, there being an upstanding dam in the lower portion of said chamber spaced inwardly from the outer portion thereof and forming an oil trough therein, a dish inwardly from said dam, first passage means including an oil passageway through said dam affording communication between said chamber and said dish, second passage means between said chamber and said dish circumferentially spaced from said first passage means, a valve controlled conduit for delivering liquid fuel from a source of supply to said chamber, said conduit means communicating with the trough in said chamber at an area of said trough that is in non-communication with the oil passageway through said dam for at least substantially

5 half the extent of the trough and at a point more adjacent to said second passage means than to said first passage means, means for supplying air to said chamber, means for supplying primary combustion air to said pot, and means in the upper part of said pot for supplying secondary combustion air.
